ELASTIC FABRIC

George W. Lindley, Philadelphia, Pa.

Application March 31, 1933, Serial No. 663,683

12 Claims. (Cl. 66—192)

This invention relates to elastic fabrics; and it has reference more particularly to elastic fabrics especially suitable for the manufacture of corsets and the like.

5 Due to being made either wholly or in part from elastic material, corsets and similar garments clinging tightly to the body thereby inducing sweating with attendant discomfiture to the wearer especially in hot weather. With the materials heretofore employed for the manufacture of corsets, little opportunity was afforded for exudation since the fabrics were generally either of close woven or close knit textures.

10 The chief aim of my invention is to overcome the drawback to which attention has been directed, and this desideratum I attain through provision of a porous fabric possessing the requisite elasticity for use in corset manufacture, and by virtue of its porosity, permitting ready evaporation of perspiration when the corsets are worn.

15 A further object of my invention is to secure the indicated attributes in a porous fabric which lends itself to very economic manufacture on warp knitting machines.

20 Other objects and advantages will be manifest from the detailed description following of the attached drawings, wherein Fig. I is a fragmentary view showing the front face of porous fabric embodying my invention in one form.

25 Fig. II is a view similar to Fig. I showing a modified form of my improved fabric.

Fig. III is an enlarged view of a fragment of the fabric shown in Fig. I; and

30 Fig. IV is a view corresponding to Fig. III showing the texture of the modified embodiment of Fig. II.

35 With reference first more particularly to Figs. I and III, the fabric there illustrated has spaced parallel wefts 10 of relatively heavy covered rubber yarn which are bound in by a series of laterally spaced loop chains 11, 12 formed from non-elastic yarns 13, 14 of finer gage, said loop chains being crosswise connected as at 15 in the intervals between adjacent wefts 10 of the elastic yarn 40 thereby defining the interstices 16 of the fabric. The loop chains 11, 12, it will be observed, are double, that is to say, each of them is formed from two warp yarns 13, 14, which, for convenience of distinction, have been indicated 45 plain and stippled in Fig. III. In the chains 11 the wefts 10 are engaged between a loop 19 at the face of the fabric formed from the yarn 13, and a substantially opposite loop 20 formed at the back of the fabric from the yarn 14, whereas in 50 the chains 12 the said wefts are engaged between

a loop 21 at the front of the fabric formed from the yarn 14 and a substantially opposite loop 22 formed at the back of the fabric from the yarn 13. Thus the embracing loops at the front of the fabric are formed by the yarns 13, 14 respectively in alternate chains 11, 12. A further characteristic to be noted from Fig. III is that the spacing of the wefts 10 is determined by substantially opposite loops 23, 24 and 25, 26 in the chains 11 and 12 intervening the embracing loops 19, 20 and 21, 22, said intervening loops being formed from the yarns 13, 14 and joined by the lateral connections 15 which, as previously mentioned, set apart the interstices 16. As shown, all the component loops of the open foundation web of the fabric are tightly drawn so that said fabric is secure against longitudinal distortion, while the openness of the knitted ground web freely permits stretching of the weft 55 yarns 10.

20 Elastic fabric having the described characteristics I preferably produce in continuous strip form on a flat warp knitting machine equipped with a suitable feed for laying the elastic yarn back and forth between the double courses formed by the two sets of needles, and afterwards cut to different lengths as required in the manufacture of corsets and like garments. Moreover, as an aid to such cutting, I preferably form, at proper intervals lengthwise of the strip incident to the 30 knitting thereof as aforesaid, solid transverse bands across which I cut centrally to sever the pieces with incident formation along opposite edges of each cut piece, ornamental margins such as shown at 27 in Fig. I. As illustrated, this 35 margin 27 is formed by triple grouping of the elastic weft strands 10 and by incorporation of the component strands of these groups between the loops of successive double courses of the knitting instead of by the loops of alternate 40 courses as described of the body portion of the fabric. The raw cut edges may be finished off against ravelling in any suitable manner, for example, by overedge stitching as conventionally indicated at 28.

45 In the modified fabric of Figs. II and IV, the interstices 16a are larger than those of the first described form due to interposition in this case of three pairs of the loops 23a, 24a and 25a, 26a between the embracing loops 19, 20 and 21, 22 50 of the chains 11a, 12a respectively, so that a correspondingly greater spacing of the wefts 10a is predetermined. A further variation of the modified fabric of Figs. II and IV will be noted in the somewhat different construction of the mar- 55

gin 21a wherein the wefts 10a are engaged throughout between the registering loops of the successive double courses of the knitting. In all other respects the modified fabric is identical with the first described form, and I have accordingly designated all corresponding parts which have not been specifically mentioned, with the same reference characters hereinbefore employed except for the addition in each instance of the letter "a" for the purposes of distinction.

It is to be understood that I do not consider myself limited to the precise details of construction and arrangement herein set forth since various other modifications can be made within 15 the scope of the appended claims without departing from the spirit of my invention.

Having thus described my invention, I claim:

1. Porous warp-knit fabric suitable for corsets and the like, having spaced parallel strands of 20 elastic yarn incorporated between opposite loop chains of inelastic yarns respectively at the front and the back of the fabric, said chains being connected laterally in the intervals between adjacent elastic strands throughout the width of 25 the fabric with their connecting portions defining the interstices of the fabric.

2. Porous warp-knit fabric suitable for corsets and the like, having spaced parallel wefts of relatively heavy elastic yarn incorporated between 30 opposite loop chains of inelastic yarns of finer gage respectively at the front and the back of the fabric, said chains being connected laterally in the intervals between adjacent elastic strands with their connecting portions defining the interstices of the fabric.

3. Porous warp-knit fabric suitable for corsets and the like, having parallel strands of elastic 40 yarn inlaid between registering embracing loops of laterally spaced double loop chains, adjacent elastic strands being held in spaced relation and the interstices of the fabric defined by laterally connected registering loops intermediate the embracing loops aforesaid of the double chains.

4. Porous warp-knit fabric suitable for corsets and the like, having spaced parallel strands of 45 elastic yarn incorporated by loop chains connected laterally in the intervals between adjacent elastic strands with the connecting portions defining the interstices of the fabric, each such chain being knit from two warp yarns with the elastic strands inlaid between embracing loops at opposite sides of the fabric.

5. Porous warp-knit fabric suitable for corsets and the like, having spaced parallel strands of 55 elastic yarn incorporated by loop chains connected laterally in the intervals between adjacent elastic strands with their connecting portions defining the interstices of the fabric, each such chain being knit from two warp yarns with the elastic strands inlaid between registering embracing loops of the respective warp yarns, and said loops being respectively disposed at opposite sides of the fabric in adjacent chains.

6. Porous warp-knit fabric suitable for corsets and the like, comprising a portion wherein spaced parallel strands of elastic yarn are incorporated by loop chains of inelastic yarns, said chains being connected laterally in the intervals between adjacent elastic strands with their connecting portions defining the interstices of the fabric; and a solid portion wherein the elastic strands are bound together in non-spaced contiguous relation by the loop chains.

7. Porous warp-knit fabric suitable for corsets and the like, comprising a portion wherein spaced parallel wefts of elastic yarn are incorporated by loop chains of inelastic warp yarns, said chains being connected laterally in the intervals between adjacent elastic wefts with their connecting portions defining the interstices of the fabric; and a solid portion wherein the elastic wefts are bound together in non-spaced contiguous relation by said loop chains.

8. A double faced knitted fabric comprising elastic weft threads disposed between the opposite faces of the fabric and secured in place by separate pairs of warp thread loop chain portions extending from face to face of the fabric and forming said opposite faces of the fabric.

9. A double faced elastic fabric comprising substantially similar opposite faces including adjacent separate loop wale portions formed by successive loop courses, extending alternately between said faces and elastic wefts bound in predetermined courses respectively between the loops of the opposite faces of the fabric formed by said courses.

10. A double faced knitted fabric comprising elastic weft threads disposed between the opposite faces of the fabric and secured in place by separate pairs of warp thread loop chain portions extending from face to face of the fabric and forming said opposite faces of the fabric.

11. A double faced elastic fabric comprising substantially similar opposite faces including adjacent separate loop wale portions formed by successive loop courses, and elastic wefts bound in predetermined courses respectively between the loops of the opposite faces of the fabric formed by said courses, said wefts being tied in position in said fabric by warp threads crossing said wefts and forming loops in each of said successive wale loop course portions on the opposite faces of the fabric respectively.

12. Porous warp-knit fabric suitable for corsets and the like, having parallel strands of elastic 55 yarn inlaid between registering embracing loops of laterally spaced double loop chains, adjacent elastic strands being held in spaced relation and the interstices of the fabric defined by laterally connected registering loops intermediate 60 the embracing loops aforesaid of the double chains.

GEORGE W. LINDLEY.
